The ornamental design for a basket, as shown and described.

DESCRIPTION

FIG. 1 is an isometric view of a basket showing my new design, showing the top, front, and right side thereof, the opposite side being a mirror image thereof.

FIG. 2 is an isometric view thereof, showing the bottom, rear, and right side thereof, the opposite side being a mirror image thereof.

FIG. 3 is a front elevational view thereof, the rear elevational view being a mirror image thereof.

FIG. 4 is a top plan view thereof.

FIG. 5 is a bottom plan view thereof.

FIG. 6 is a left side elevational view thereof, the right side elevational view being a mirror image thereof; and, FIG. 7 is a front elevational view thereof, showing the handle in an alternate, raised position.
